(57) CLAIM

I claim the ornamental design for a cup cake bottle, as shown and described.

DESCRIPTION

FIG. 1 is a front view of the cup cake bottle showing my new design;

FIG. 2 is a rear view thereof;

FIG. 3 is a side view thereof;

FIG. 4 is an opposite side view thereof;

FIG. 5 is a top view thereof;

FIG. 6 is a bottom view thereof;

FIG. 7 is a perspective view thereof; and,

FIG. 8 is an alternative perspective view thereof with the bottle cap removed.
